UNITED STATES PATENT OFFICE

HEYMAN ROSENBERG, OF NEW YORK, N. Y.

HEAT TREATING APPARATUS FOR METAL WORK

Application filed August 20, 1931. Serial No. 558,413.

In the case-hardening and other heat treating of small metal articles, I have found the apparatus disclosed in my U. S. Letters Patent No. 1,786,508, dated December 30, 5 1930, and also the apparatus disclosed in my co-pending applications, one filed September 24, 1929, Serial No. 394,832, and the other filed April 29, 1930, Serial No. 448,349, gratifyingly efficient for the purpose intended, and it is one of the objects of the present invention to provide an apparatus for treating larger articles, which apparatus is susceptible by very slight modification of being transformed into substantially the same 10 or the mechanical equivalent of the same apparatus as set forth in my said patent and pending applications, so that the present improved apparatus is well adapted for use primarily for the treatment of larger articles while enabling the user, without any substantial expense, to transform the plant into one for treating the smaller articles and again transform the plant to its present adapted use. 15 It should be understood, therefore, that through various details of my said patent and pending applications, and other of my pending applications, have been omitted from the disclosure in the accompanying drawings, such omission is for the purpose of clarity of disclosure of the new matter, and such details may be used with such new matter or in the transforming of the plant for the treatment of the smaller articles to any extent found available and desirable; and, to that end, reference is had to my said patent and pending applications for details such as are susceptible of ready application to and use with the plant herein set forth. 20 It should, of course, be understood that while the present improved plant is especially adapted for the treating of larger articles as compared with the smaller articles of said patent and pending applications, the term "larger" must be accepted in its relative sense and limited to physically available possibilities, as, for example, the smaller articles, while not to be definitely limited, may be represented by such products as screws, screwnails, washers, nuts, bolts, and the like, and the larger articles, while not to be definitely limited, may be pinions, gears, discs, and like devices such as are commonly employed in automobile construction, and the range of sizes will be limited only by the available physical capacity of the work holders and containers provided. The actual size of the article to be treated, therefore, is not to be considered a determining factor except where it is too small or too large to be conveniently or effectively handled by the apparatus disclosed. 25 Among the objects in view is the successive heat treatment of articles of metal work under conditions affording effective results at an expenditure of minimum cost and minimum time. 30 Another important object is the arrangement of the plant as a condensed unit for a substantial saving of space. 35 All of the numerous objects set forth in my above-mentioned patent and pending applications are also true of the present invention as applied to the treatment of larger articles, and specifically true of the plant when transformed for the treatment of smaller articles. 40 A still further and more detailed object is the ready transporting of a work holder successively to successive points of treatment by mechanical apparatus not requiring manual intervention for the location, deposit or detachment of the work holder from its carrying means, and in this connection a still more specific object is the swinging of the work holder through an arc from point to point for successive treatment without the necessity for complicated or expensive vehicles of transportation. 45 With these and other objects in view as will in part hereinafter become apparent and in part be stated, the invention includes the provision of successive heat treating apparatus and simple, easily-operated means for detachably transporting work holders successively to the points of treatment. 50 The invention also includes housings or enclosures for all such apparatus for conserving heat, preventing the work holders

55

60

65

70

75

80

85

90

95

100

from exposure to chill during transportation from point to point, and for exhausting vapors and gases without releasing the same into the space occupied by operators.

5 The invention also comprises certain other novel constructions, combinations, and arrangements of parts as will hereinafter be made clear and be subsequently pointed out in the appended claims.

10 In the accompanying drawings.—

Figure 1 is a longitudinal, vertical, central section through a completely organized plant embodying the features of the present invention, parts being seen in elevation.

15 Figure 2 is an enlarged, detailed, fragmentary sectional elevation of one of the work holder arms and adjacent parts, showing a work holder in position.

20 Figure 3 is a side elevation of the same parts seen from a plane at right angles to the plane of the section of Figure 2.

25 Figures 4, 5, and 6 are further enlarged, detailed elevations showing the successive positions of the pick-up hook for the work holder, cooperating parts being seen fragmentarily in elevation and in section.

30 Figure 7 is a top plan view of the discharging tray from the quenching bath seen detached, and shown on a scale approximately that of Figures 2 and 3 but slightly smaller.

35 Figure 8 is a fragmentary, sectional elevation of the parts seen in Figure 7, the section being taken on the plane indicated by line 8—8 of Figure 7.

Figure 9 is a transverse, vertical section taken on the plane indicated by line 9—9 of Figure 8.

40 Figure 10 is a fragmentary, enlarged, vertical section taken transversely through one of the marginal parts of the discharge tray at the place of the pivot pin for the work holder receiving cradle.

45 Figure 11 is an inverted plan view of a work holder detached.

Figure 12 is an enlarged, detailed elevation of one of the arms of the work holder showing the preferred serrated form of its upper edge for facilitating retaining articles of work in spaced relation.

50 Referring to the drawings by numerals, 1 and 2 indicate furnaces, and 3 a quenching vat arranged preferably as seen in alinement and having the upper areas above them enclosed in a suitable hood or housing 4 provided with discharge flues 5, 5, for carrying off the gases, fumes, and volatiles from the plant. The flues 5 are, of course, preferably connected with appropriate draft apparatus, not illustrated, and the velocity of the draft may be controlled by slide dampers 6 to insure against escape of objectionable fumes into the room or other area outside the treating apparatus. A receiving table 7 is arranged adjacent the vat 3 and in

line with the several parts of the plant, the table being preferably sustained on a framework 8 supporting a hopper 9, which hopper is not used while the table 7 is employed, but the hopper 9 is intended for use when the plant is transformed into one for treating smaller articles, as will be readily understood by reference to my above-mentioned patent.

75 The furnaces 1 and 2 are, of course, susceptible of a wide range of variation. One form of furnace found to be quite acceptable is that utilizing gas as a fuel, but the invention is not to be limited to the character of fuel or types of furnace employed.

80 Mounted on and forming part of the cover of each furnace 1 and 2 is a plate 10 which is centrally apertured to accommodate the passage of a receptacle or housing mounted to detachably extend into the furnace, the said receptacle being indicated at 11 for furnace 1 and at 12 for furnace 2. Receptacle 11 is preferably of the type adapted to take the place of the common drum or like housing customarily employed in preheating articles to be tempered, and the receptacle 12 is preferably a pot for containing cyanide in a molten condition, or like treating bath. The vat 3 is supplied with water or oil, or other appropriate quenching fluid, and its temperature is preferably maintained low by circulation after the manner set forth in my above-mentioned patent.

85 As clearly seen in Figures 5 and 6, each of the receptacles 11 and 12 (12 only being seen in these figures) is provided with a peripheral flange 13 at its upper edge which overhangs and rests on plate 10, or other parts of the cover of the respective furnace. At 90 the line of juncture between the flange 13 and the respective receptacle 11 or 12 the wall of the receptacle is rounded at 14 to prevent the presentation of a sharp edge, and to aid in the camming action of the 95 work holder as hereinafter mentioned.

100 The furnaces 1 and 2 and the vat 3, as well as frame 8, may be and are preferably rigidly connected together so as to stand as substantially a continuous framework, and the mounting of various parts hereinafter described on that framework is controlled largely by the consideration of facility, convenience, and effectiveness of location. With this in mind, there outstands from the 105 said framework, and preferably from that part of it making up the plate 10 of furnace 2, a pair of sleeves 15 in which is journaled a shaft 16 which shaft extends through pendent eyes 17 of an operating lever 18, which is bifurcated to produce arms 19 and to provide a space between said arms through which a work holder may be swung. These parts are arranged at that side of furnace 2 adjacent furnace 1 so that the arms 19 over- 110

hang the furnace 1 with the free ends of the arms 19 extending beyond the transverse center line of the receptacle 11.

At the opposite side of furnace 2 and carried by the framework of the plant, and preferably that part making up the plate 10 of furnace 2, are upstanding sleeves 20, 20, identical in form and arrangement with sleeves 15 except that they do not upstand quite so high to accommodate the movement of the parts carried thereby. A shaft 21 is journaled in the sleeves 20 and keyed or otherwise fixed to eyes 22 pendent from lever 23, the shaft 21 being identical with shaft 16, eyes 22 with eyes 17, and lever 23 with lever 18, the lever 23 being bifurcated to provide arms 24 similar to arms 19. These parts being identical will be understood to be disclosed on an enlarged scale in Figures 2 and 3, though these figures specifically show only the lever 23 and its connected parts.

Each of the shafts 16 and 21 extends transversely of the plant to beyond the side thereof and is provided with actuating mechanism, such as illustrated and described in my above-mentioned patent and pending applications, so that the shafts may be readily rocked or oscillated to swing the levers from positions in advance to positions in the rear, as indicated in dotted lines in Figure 1 with respect to lever 23.

Each of the levers 18 and 23 carries a means of pick-up and let-go for work or a work-holder, so that the work or work-holder may be lifted by one of the levers from its position in one of the receptacles and moved by the lever and released in the other receptacle, and then picked up by the second lever and moved from the second receptacle to the quenching bath, and there released to be discharged by the discharging tray of the quenching bath. As the pick-up and let-go for the two levers 18 and 23 is identical mechanism, but one is illustrated in detail and seen in Figures 2 to 6 inclusive. Connecting the two arms of the respective lever substantially at their free ends is a cross rod 25 on which is freely, pivotally mounted a pair of pick-up hooks 26, each hook having its lower end tapered below the hook to provide a camming edge 27. As a means for preventing the hooks 26 from sliding along the rod 25 and to keep them centered on the rod, a sleeve 28 is interposed between the hooks and is anchored to the rod 25 in any appropriate manner, as by a set screw 29. The material from which the hooks 26 are formed is extended an appreciable distance beyond the rod 25 to provide counterbalance plates 30, 30, and said plates are clamped together by a through bolt 31 and held spaced apart by a sleeve 32 surrounding the bolt 31. The counterbalance thus produced is possessed of sufficient

weight to allow the hooks 26 to depend substantially vertically, but incident to such counterbalance the hooks 26 swing very easily and freely, and to render the counterbalance in action effective to the end of causing the hooks to swing with ease, an adjustable weight is preferably provided for the counterbalance and may assume the form of a bolt 33 threaded into the sleeve 32 and carrying a nut 34 which is adapted to be threaded inward or outward along the bolt 33 according to whether the effective weight of the counterbalance is to be decreased or increased relative to the hooks 26.

In the operation of the levers 18 and 23, their pick-up and let-go hooks 26 are adapted to cooperate with any appropriate work holder having a properly located cross bar to receive the hooks and a properly located camming surface to shift the holder laterally for releasing the hooks, and otherwise the work holder may be of any appropriate form or contour adapted for cooperating with the receptacles 11 and 12. One appropriate and effective form of work holder, where the work is in the nature of gears, rings, and the like, is illustrated in the accompanying drawings and consists of an upright bar 35 having a number of outstanding arms 36 spaced throughout the length of the bar 35 and having at its lower end rest bars 37 provided with feet 38 on which the structure is adapted to rest when placed on a table or like support. The upper end of the bar 35 is formed integral with or otherwise appropriately fixed to a cross bar 39 outstanding laterally on opposite sides of a suspension and camming bar 40 which is formed integral with or otherwise fixed to the bar 35 and located to extend in a direction fore and aft relative to the bodily travel of the parts being shifted by the levers 18 and 23. The bar 40 is referred to as a suspension bar because, when the work holder is located in either of the receptacles 11 or 12, the terminals 41 of the bar rest on the outstanding flange of the respective receptacle while the bar 35 hangs pendent in the receptacle; and the bar 40 is referred to as a camming bar because its end portions beneath the projections 41 are formed with inclined faces 42, 42, located to center the work holder in the respective receptacle when lowered into the same slightly off center. This centering action is the result of a camming movement occasioned by one of the cam faces 42 striking the curved portion 14 of the respective receptacle 11 or 12.

It is to be observed that the length of each of the levers 18 and 23 is such that the axis of the pivot of hooks 26 extends substantially beyond the vertical axis of the respective receptacles 11 and 12 when the levers are in their lowermost positions as seen in full lines in Figure 1, and the spacing

of the shaft 16 laterally of the vertical axis of the receptacle 12 is such that the pivotal axis of hooks 26 of lever 18 lies beyond said vertical axis of receptacle 12 when the lever 5 18 is swung through approximately one hundred eighty degrees or a little more and brought to a position with the free ends of its arms 19 overhanging the receptacle 12. Hence, when the lever 18 is in a raised position 10 and a work holder is manually or otherwise positioned in receptacle 11, and the lever 18 then lowered down over the receptacle, the cross bar 25 will move to a position beyond the vertical planes of cross bar 15 39 and the camming faces 27 of hooks 26 will strike the cross bar 39 and ride rearwardly thereon until the bite of the hook passes below the line of bar 39, and as soon as this occurs the hook will swing toward the cross 20 bar 39 until the bite of the hook underhangs the cross bar so that, if the lever 18 is then lifted upward, the hooks will come into lifting engagement with the bar 39. It will be observed that the housing or enclosure 4 will 25 be properly provided with doors and openings for access to various parts, and to this end it is preferable to have the end wall 43 of the housing terminate short of the full length of the housing, that is have its edge 30 spaced sufficiently above the plate 10 of furnace 1 to leave an entrance opening 44 for the successive introduction of the work 35 holders.

The hooks 26 of lever 18 having engaged the work holder, rotation of shaft 6 clockwise will cause the lever 18 to be swung to a position overhanging the receptacle 12. During this movement, the work holder and its work will have remained suspended in a 40 vertical position while relatively travelling through the opening between the arms 19 so that the work holder is lowered into the receptacle 12 in the pendent, vertical position. It will be borne in mind that since the rod 45 25 is spaced from the axis of movement of lever 18 sufficiently to lie beyond the rod 39, when the work holder is in receptacle 11, the pivot rod 25 will likewise extend beyond the vertical axis of receptacle 12 at the other side 50 thereof from its location with respect to receptacle 11, and thus as the lever 18 lowers the work holder into receptacle 12, the work holder will enter the receptacle off-center with respect to the receptacle, and the rear 55 camming edge 42 will thus be caused to engage the curved portion 14 of receptacle 12, and will cam the work holder laterally, that is, in a direction of the length of the bar 40 until the cross bar 39 of the work holder 60 reaches a central position with respect to receptacle 12. This shifting movement results in the location of the cross bar 39 nearer the shaft 16 than is the bar 25 when lever 18 is lowered down across receptacle 12. 65 Thus, as the suspension and camming bar 40

reaches its final, seated position on receptacle 2, the hooks 26 of lever 18 being swung out of a vertical line relative to their pivotal axis tend to swing back to that line and a further lowering movement of lever 18, after 70 the seating of the bar 40, releases the hooks 26 from their engagement with bar 39 and allows them to swing to a vertical position entirely free of that bar. Then the lever 18 may be swung back to its former position 75 overhanging receptacle 11 while leaving the deposited work holder in its position suspended in receptacle 12. On the return movement of lever 18, the hooks 26 engage the bar 39 of the newly located work holder 80 which has been introduced while the lever 18 has been depositing the former work holder in receptacle 12.

The action of the pick-up and let-go hooks 26 as thus described is made clear from Figures 4, 5, and 6. In these figures the lever itself has been omitted for the sake of clarity and only the pivot bar 25 illustrated. When lever 18 is lowered across the receptacle 11, the hooks 26, as seen in Figure 4, descend to engagement with and cam across the bar 39, as indicated in dotted lines in Figure 4. When the hook has reached the dotted line position in Figure 4, it is only necessary to elevate it to bring it into lifting engagement with the cross bar 39, and then, when the parts have been swung from receptacle 11 to receptacle 12, the suspension and camming bar 40 is cammed to a centering position as indicated in Figure 5, 90 as the work holder is being lowered into the receptacle 12, and when bar 40 has become centered, the hooks 26 will have moved from the full line position of Figure 5 to the dotted line position thereof, so that a further lowering movement of the cross bar 25 and the parts which carry it will cause the hook 26 to clear the cross bar 39 so that the hooks 26 move from the dotted line position of Figure 6 to the full line position thereof, or approximately so, and the hooks are then entirely free to be lifted without danger of engagement with cross bar 39.

The action of the hooks 26 of lever 23 is identically that just described except that the work holder is picked up from the receptacle 12 and deposited in the tray 45 in quenching vat 3, and while the release of the hooks is accomplished in identically the same manner as that just described, the apparatus arranged within the tray 45 to receive the work holder is slightly different from the receptacles 11 and 12, and such apparatus is seen in detail in Figures 7, 8, and 9. It is, of course, obvious that practically identically the same type and arrangement of receptacle might be provided within vat 3, or at least a support having the same marginal arrangement, and an op- 115 120 125 130

erating lever identical with levers 18 and 23 might well be used for picking the work holder up out of the quench and depositing it on the table 7, but because the plant is intended for and adapted to conversion for treatment of small articles after the manner set forth in my above-mentioned patent and pending applications where the articles fall freely into the tray 45 and are discharged therefrom by swinging the tray to a discharging position somewhat similar to the dotted line position in Figure 1, it is desirable to provide means adapted to cooperate with lever 23 and its hooks 26 to receive the work holder within the tray 45, so that the tray can serve as the means for discharging the work holder. The tray 45 is a reticulated basket fixed to a rock shaft 46 extending laterally beyond the housing to appropriate operating mechanism, such as illustrated and described in my above-mentioned patent and pending applications. The opposite edge of the tray 45 from that supported by the shaft 46 is preferably provided with a bracket or brackets 47 adapted to overhang and engage a rail or like support 48 forming part of the vat 3 or the framing thereof.

Therefore, to enable the tray 45 to serve as the receiver and discharging means for the work holder to and from the vat 3, a cradle or pivotally mounted framework is carried by the tray and located to receive and cooperate with the work holder delivered by lever 23 and its hooks 26 exactly as receptacle 12 cooperates with and receives the work holder from lever 18 and its hooks 26. That frame or cradle, as clearly seen in Figures 7, 8, and 9, consist essentially of longitudinal bars 49, 49, and cross bars 50, 50, connecting the bars 49. The bars 50 may be merely in the form of bolts or rods, while the bars 49 are preferably angle bars and from the horizontal web of each bar at a central point thereof there depends a weight 51 preferably carried by a rod or bolt 52 anchored to the respective angle bar. Outstanding laterally from each of said angle bars midway of the length thereof is a bracket 53, as best seen in Figures 7 and 8, each of which brackets is bifurcated at its free, downturned end portion to provide a fork 54 adapted to engage and extend on opposite sides of a pivot pin 55, there being a pivot pin 55 fixed to and extending inwardly from each side of tray 45. Obviously, the pins 53 may be provided in any appropriate manner, but preferably consist of bolts extending through the marginal portions of the tray 45 and engaged at their outer ends by nuts 56, as best seen in Figure 10. Each bolt is shouldered at the inner face of the tray so that the nut 56 may effectively clamp the bolt in place and leave an inwardly-extending pivot finger. Ob-

viously, by backing off the nut 56 the part 55 in each instance may be readily removed to leave the tray free of obstruction when the plant is transformed for the handling of small articles.

Thus it will be seen that the framework made up of parts 49 and 50 will lie constantly in a horizontal position owing to the action of the weights 51 and the fact that the parts are pivotally mounted on the fingers 55, and this position is maintained notwithstanding the swinging of the tray 45 to and from the dotted line position seen in Figure 1. Each rod 50 is formed preferably midway of its length with a depression 57 located to receive the suspension and camming bar 40 and to center the work holder lowered into engagement with said depressions 57. In other words, the bars 50 are in that relation to the pivot of lever 23 and the pivot rod 25 of lever 23 that, when lever 23 is lowered above the tray 45, the camming face 42 at the rear end of bar 40 will strike the rear rod 50 and cam the work holder to a centering position forward of its location at the time of its being lowered by the hooks 26, so that the hooks 26 are swung to an inclined position such as indicated in dotted lines in Figure 6, and the further lowering of the lever 23, therefore, frees the hooks from the cross bar 39 and allows the lever 23 to return to its former position while leaving the work holder suspended on the cradle.

When the work holder has thus been deposited in the tray 45, and the chilling action has been completed, the shaft 46 is oscillated to swing the tray 45 to the dotted line position of Figure 1, in which position the work holder will rest on its feet on the table 7, and further lowering of the tray will allow the cradle to move sufficiently below the bar 40 to allow the work holder to be readily manually removed. By preference, a part of the housing 4 includes a door 58 pivoted at 59 and connected pivotally by a link 60 to a part of the frame of tray 45, so that the door will open in advance of a discharging movement of the tray and will follow the tray and close as the tray returns to its position in vat 3.

It will thus be seen that the only manual effort required is the lowering of the work holder into receptacle 11 and the removal of the work holder from the table 7, and it should be apparent that even these manual operations could be easily disposed of where desired by merely providing take-up and let-go levers and hooks in advance and in the rear of the plant corresponding to the lever 18 and hooks 26; but for most practical purposes it has been found preferable to load the work holder manually and then deposit the work holder manually to start the process of the plant.

100

105

110

115

120

125

130

It should also be observed that the whole process is one of heat treatment, that in receptacle 11 being preheating, that in receptacle 12 being further heating and further 5 treating as by carbonizing through the action of a cyanide bath or the like, and that in the vat 3 being heat treating in the sense of quick heat exhaustion or quick lowering of temperature, and to avoid a negative view- 10 point of the action in vat 3, it is believed correct to describe the action as heat treatment, being merely a downward heat treatment instead of an upward heat treatment.

While the invention is in no sense limited 15 to any particular mounting of work on the work holder or any particular form of the work holder, it is nevertheless a fact that for certain work, such as work made up of circular bodies having openings there- 20 through, including gears and the like, it is desirable to suspend them on arms, such as the arms 36, and to prevent possibility of parts of work moving or undesirably sliding toward each other when suspended on 25 the same arm, I prefer to provide serrations or tooth-like projections 61 on the upper edge of the arms 36, as seen in detail in Figure 12. Also, at the outer end of each arm an upstanding finger 62 is a convenient arrange- 30 ment to prevent the work accidentally slipping off of the arm.

While the present invention is especially well adapted for the treatment of articles of metal work for case-hardening or like 35 tempering, it is not necessarily limited to any such apparatus and is well adapted for any of numerous forms of heat treatment of work articles for known and desirable results.

40 40 What is claimed is:—

1. In heat treating apparatus, the combination, with means providing a plurality of places of heat treatment, of work holder positioning means at each of said places, and 45 pick-up means cooperative with said work holder positioning means for bodily moving a work holder from one place of heat treatment and at another place of heat treatment depositing and releasing the work 50 holder from the pick-up means.

2. In heat treating apparatus, the combination, with means providing a plurality of places of heat treatment, of work holder positioning means at each of said places, and 55 pick-up means cooperative with said work holder positioning means for bodily moving a work holder from one place of heat treatment through an arc to and at another place of heat treatment depositing and releasing 60 the work holder from the pick-up means.

3. In heat treating apparatus, the combination, with means providing a plurality of places of heat treatment, of work holder positioning means at each of said places, and 65 pick-up means cooperative with said work

holder positioning means for bodily moving a work holder from one place of heat treatment through a vertical arc to and at another place of heat treatment depositing and releasing the work holder from the pick-up 70 means.

4. In heat treating apparatus, the combination, with means providing a plurality of places of heat treatment, of work holder positioning means at each of said places, and pick-up means cooperative with said work holder positioning means for bodily moving a work holder upward out of one place of heat treatment and out of contact with supporting means other than said pick-up 80 means and for moving the work holder to and lowering it into another place of heat treatment, and depositing and releasing the work holder at the second-mentioned place 85 free of said pick-up means.

5. In heat treating apparatus, the combination, with means providing a plurality of places of heat treatment, of work holder positioning means at each of said places, work holder carrying means mounted to reciprocate between the places of heat treatment, and means on the work holder carrying means cooperative with said work holder positioning means for automatically picking up a work holder at one of the places of heat treatment and for automatically releasing the work holder at the other. 95

6. In heat treating apparatus, the combination, with means for providing a plurality of places of heat treatment, of work holder carrying means mounted to move between the places of heat treatment, a hook comprised in said carrying means being pivotally dependent from a part thereof and located with its pivot disposed with relation to the places of heat treatment to extend at one side of the place of engagement of the hook with a work holder for causing the hook to engage and release the work holder for automatically lifting the work holder from one place of heat treatment and depositing and releasing it at another. 100 105 110

7. In heat treating apparatus, the combination, with means providing a plurality of places of heat treatment, of work holder carrying means mounted to move between the places of heat treatment, a hook comprised in said carrying means being pivotally dependent from a part thereof and located with its pivot disposed with relation to the places of heat treatment to extend at one side of the place of engagement of the hook with a work holder for causing the hook to engage and release the work holder for automatically lifting the work holder from one place of heat treatment and depositing and releasing it at another, and means for automatically shifting the work holder relative to the pivot of said hook for effecting 115 120 125 130 releasing movement of the hook.

13. The combination, with means providing a plurality of places of heat treatment, and a work holder adapted to cooperate therewith, of a lever pivoted to swing from 5 a position overlying one of the places of heat treatment to a position overlying the other, said lever being bifurcated and provided with an opening of a size sufficient to accommodate the passage of the work holder, a 10 hook pivotally carried by the lever adjacent the free ends thereof adapted to engage the work holder for moving the same from one place of heat treatment to the other, and means for shifting the work holder on reaching 15 the second place of heat treatment for releasing the engagement of the hook.
14. In heat treating apparatus, the combination of means providing a plurality of places of heat treatment, means for shifting 20 a work holder from one place of heat treatment to another place of heat treatment, a pivotally mounted cradle at the last-mentioned place of heat treatment for receiving and sustaining the work holder in a vertical position, and means for swinging the cradle from the place of heat treatment to a discharge position while maintaining the same with the work holder in a vertical position.
- 25 15. In apparatus of the class described, the combination, with a discharge tray for heat treated work, of a cradle pivoted thereto and counterbalanced to maintain a horizontal position, said tray having means for receiving and sustaining a work holder in a vertical, suspended position.

In testimony whereof I affix my signature.
HEYMAN ROSENBERG.
